United States Patent Office

Des. 232,586
Patented Aug. 27, 1974

232,586

CHECKWRITER

Joseph K. Dikoff, 4 Privateer, Apt. 3,
Marina Del Ray, Calif. 93933

Filed July 12, 1973, Ser. No. 378,777

Term of patent 14 years

Int. Cl. D18—01

U.S. Cl. D64—11 B

FIG. 1

FIG. 2

FIG. 3

FIG. 4

FIG. 5

FIG. 6

FIG. 1 is a perspective view of a checkwriter showing my new design;

FIG. 2 is a top plan view thereof;

FIG. 3 is a right side elevational view thereof;

FIG. 4 is a left side elevational view thereof;

FIG. 5 is an elevational back view thereof; and

FIG. 6 is an elevational front view thereof.

I claim:

The ornamental design for a checkwriter, substantially as shown and described.
